B. BENTELE.
HEDDLE FRAME.
APPLICATION FILED JULY 30, 1913.

1,150,012.

Patented Aug. 17, 1915.

UNITED STATES PATENT OFFICE.

BENEDIKT BENTELE, OF PATERSON, NEW JERSEY, ASSIGNOR TO ISAAC A. HALL, OF PATERSON, NEW JERSEY.

HEDDLE-FRAME.

1,150,012.

Specification of Letters Patent. Patented Aug. 17, 1915.

Application filed July 30, 1913. Serial No. 781,985.

To all whom it may concern:

Be it known that I, BENEDIKT BENTELE, a citizen of the United States, residing at Paterson, in the county of Passaic and 5 State of New Jersey, have invented certain new and useful Improvements in Heddle-Frames, of which the following is a specification.

This invention relates to heddle frames 10 and the like for looms and it has for its principal object to provide a simple, easily applied and efficient means for strengthening and stiffening such frames, especially when they are long and hence limber.

15 Another object is so to construct said means that it shall be related to the heddle supporting bars of such frames in a way calculated to brace or support them against bending or distortion, due to the weight of 20 the heddles or other influences, and at the same time be detachably connected therewith to allow the heddles to be moved past said means when adjustment thereof is necessary.

25 A further object of the invention is to construct said means so that it may be readily shifted from place to place in the frame, as a change in the number of heddles therein or other circumstances may make necessary, without unduly marring or weakening 30 the frame or any of its parts.

Other objects will appear in the course 35 of the following description of a heddle frame improved in accordance with this invention.

Referring to the accompanying drawing, wherein I have illustrated two forms of my invention, Figure 1 is a front elevation of 40 a heddle frame illustrating one form of my invention; Fig. 2 is a vertical sectional view of the heddle frame shown in Fig. 1 and on a larger scale; Fig. 3 is a fragmentary front elevation of the heddle frame shown in Fig. 1 and on a larger scale; Fig. 4 is a plan of 45 a certain clip laid out flat, the same constituting a part of the construction shown in Figs. 1 to 3; Fig. 5 is a front elevation of a heddle frame illustrating another form of my invention; Fig. 6 is a fragmentary 50 front elevation of the heddle frame shown in Fig. 5 and on a larger scale; and, Fig. 7 is a vertical sectional view of the heddle frame shown in Fig. 5 and on a larger scale.

A heddle frame of well-known type is 55 shown in the drawings; that is, it includes the end rods or uprights *a* and the hori-

zontal rods *b* jointed together in rectangular disposition. In the uprights *a* are removably arranged the ends of the heddle bars *c*, they being removable by disconnecting the 60 securing devices *d* and drawing them longitudinally out of the frame. It will be understood that the heddles are strung on these bars. As is well known, it is desirable to stiffen or strengthen a frame of this 65 character, especially if the same is long and hence limber. It is further frequently desirable to provide means to stay or brace the heddle bars *c*, which tend to bend or become distorted under the weight of the heddles or other influences and when so bent 70 and distorted interfere with the necessary perfectly free movement of the heddles supported thereon. In the most complete form of the present invention the same is adapted for the common function of stiffening or strengthening the frame and of bracing or staying the heddle bars, and at the same time the means proposed allows, by simple manipulation, the heddles to be shifted laterally as occasion requires, while the said means itself is capable of being moved to various positions in the frame without unduly marring or weakening the same, as 75 when circumstances require that the number of such means be varied.

Referring, now, to Figs. 1 to 4, the improved stiffening means is shown as consisting of two clips *e* fitted to the rods *b* and connected by the taut link *f*. Each clip *e* 80 consists of a metallic strap *g* (Fig. 4) having at its ends reverse hooks *h*. This strap is bent about the rod *b* in a manner to bring the hooked ends thereof at the inner side of the rod—thus leaving the outer side thereof clear of obstructions—said hooked ends being bent into substantially face to face 85 relation to each other. The link *f* is a metallic strap or flat bar *i* (Figs. 2 and 3) having at each end thereof an eye *j* and near 90 each end a recess formed as a slot *k* extending into the bar *i* from one edge thereof obliquely and then longitudinally of said bar. When in operative position in the frame the parts *e*, *f* are under tension, exerted by the rods *b* which, in coupling the hooked straps *g* to the link *i*, are necessarily 95 drawn together somewhat in order to engage the hooks *h* in the eyes *j*, which eyes the hooks are made to enter in the manner 100 clearly shown in Figs. 2 and 3, standing therein reverse to each other. The metal 105

of the straps *e* being somewhat stiff, when the same are made to embrace the rods *b* they exert a sufficient grip thereon to preserve them against possibility of lateral displacement. The heddle bars may be engaged in the slots *k* of the links *f* either before the latter are made to couple together the straps *e* or afterward, in which latter case each heddle bar is first sprung toward 10 the adjoining rod *b* and then forced into the slot, the oblique arrangement of the entrance end of the slot obviously facilitating this operation. In its final position it is rigidly held by the link *f* against bending or 15 becoming distorted under the weight of the heddles or other influences. It will be understood that any number of the means *e*, *f* may be employed in a single frame as circumstances require; that the said means is 20 readily removable from the frame and that any one of them may be shifted laterally to different positions on the frame without unduly marring the frame or in any way weakening it. It will be further obvious 25 that if it is necessary to shift the heddles laterally past the said means it is only necessary to spring the heddle bars toward the rods *b* until they clear the slots *k*, whereupon they may be made to pass the link *f*. 30 A clip *l* of the same reversely hooked form as the clip *e* may be employed as a means to which to attach the usual flexible connections for imparting vertical movement to the heddle frame when in the loom, 35 as shown in Figs. 1 and 5.

In the construction shown in Figs. 5, 6 and 7 the stiffening and strengthening means consists of a bar *m* having its extremities *n* bent off at right angles and adapted 40 to be secured to the inner sides of the rods *b* of the frame by short screws *o*, the said bar having slots *p* like the slots *k* already described and adapted to removably receive the heddle bars.

45 In either of the forms shown, each heddle bar being flat it is kept from undue torsional movement by the vertical part of the slot *k* or *p*, besides being prevented from unintentional displacement out of said slot on 50 account of the oblique or entrance part of the latter which requires some frictional resistance to be overcome before the bar can pass out of the slot.

One advantage present in the form of 55 frame first described and not present in the second is that shifting of the heddles past the position of the stiffening or strengthening means is possible although the frame may be so short that the heddle bars *e* cannot well be sprung out of the slots in said means, the links *f* in that case being detached from the clips *e*.

Having thus fully described my invention, what I claim as new and desire to secure by Letters Patent is:—

65 1. A heddle frame including upper and lower parallel members, upper and lower parallel bars, and frame-stiffening means joining said members and including straps, one embracing one member and the other 70 the other member, and a link having its ends detachably connected with said straps and having recesses receiving the heddle bars, substantially as described.

75 2. A heddle frame including upper and lower parallel members and upper and lower parallel flat heddle bars, in combination with a frame-stiffening device joining said members and having elongated bent slots receiving said bars and entering said device 80 obliquely and then extending longitudinally thereof, the width of each slot approximating the thickness of the bar received therein and bearing frictionally against opposite faces of the bar on moving the latter into 85 or out of said slot.

90 3. A frame of substantially the character described having upper and lower parallel members, frame-stiffening means joining said members and including a link member and a strap member embracing one of the frame members, said strap and link members having the one reversed hooks and the other an eye receiving said hooks, substantially as described.

95 4. A frame of substantially the character described having upper and lower parallel members, frame-stiffening means joining said members and including a strap member embracing one of the frame members and a link member, said strap and link members having the one reversed hooks and the other an eye receiving said hooks, said means having bracing engagement with the heddle bars, substantially as described.

100 5. A frame of substantially the character described having upper and lower parallel members, upper and lower heddle bars, frame-stiffening means joining said members and including a strap member embracing one of the frame members and a link member, said strap and link members having the one reversed hooks and the other an eye receiving said hooks, said link having slots receiving the heddle bars and extending substantially longitudinally therein, substantially as described.

105 In testimony whereof I affix my signature in presence of two witnesses.

BENEDIKT BENTELE.
